RICHARD W. MANSFIELD
By his Attorney # UNITED STATES PATENT OFFICE.

RICHARD W. MANSFIELD, OF NEW LONDON, CONNECTICUT.

GAME APPARATUS.

1,034,633.

Specification of Letters Patent. Patented Aug. 6, 1912.

Application filed August 27, 1906. Serial No. 332,100.

To all whom it may concern:

Be it known that I, RICHARD W. MANSFIELD, a citizen of the United States, residing at New London, New London county, Connecticut, have invented certain new and useful Improvements in Game Apparatus, of which the following is a full, clear, and exact description.

This invention relates to improvements in game apparatus, and particularly of the type covered by my Patent No. 779,229, dated January 3, 1905, and my Patent #830,514 dated Sept. 11, 1906.

One object is to provide a board facilitating different plays, and a second object is to provide a set of cubical lettered pieces by which the interest in competition may be increased. The new board surface is so divided or arranged that particularly interesting plays are possible, such as blockades, pursuits, refuge and capture. The new disposition of letters on the blocks increases the chances of spelling words. An additional lettered block is preferably provided 25 for use by older people and advanced players.

Figure 1 shows the outline of the board, pictures and ornamentation being omitted. Fig. 2 shows the opposite sides of the five lettered blocks or pieces which are preferably used for determining the plays. Fig. 3 shows four men, counters or scholars for moving on the board. Four are preferably provided in each of four colors, designs or figures. Fig. 4 shows the opposite sides of an extra or additional block or piece. Piece numbered 1 bears the letters A—I—F—G—L—R. Piece 2 has letters E—O—H—J—P—V. Piece 3 has letters I—Y—C—M—X—Z. Piece 4 has letters A—O—B—Q—S—T. Piece 5 has letters E—U—D—K—N—W. Piece 6 has extra consonants. The schoolhouse designation 7 in the center is surrounded by a yard 8 divided into 45 spaces, preferably a double row, and at intervals are safety spaces or steps such as 9—9—9—9. In the corners also are safety spaces 10—10—10—10 forming the entrances to the yard from the paths or roads 50 11—11—11—11, which lead from the homes 12—12—12—12. The roads are preferably marked off or divided into spaces, so that the yard or home may be gradually approached depending on which direction the 55 player is moving, but if desired they may be ignored or omitted, so that the players will

pass by a simple move from a yard to a home, and vice versa.

The following is a part of the description, together with illustration of the board 60 which was entered according to act of Congress, in the year 1906 by me, RICHARD W. MANSFIELD, in the office of the Librarian of Congress, at Washington, under the title "Spelling Bee at the School of Nathan 65 Hale":

"The game was developed and improved to realize the fun and excitement of the old spelling bee, which sharpened the wits and aroused the desire to 'spell down the class.' 70 The board represents the town. The homes in the corners are separated by broad fields. In the center of the town is the little red school house. Roads lead to the school house yard from each of the homes. 75

"The families of scholars start out from their homes to go around the school house to the right and return home. When two people play, each has four scholars in his family. Three people have three scholars 80 each. Four people will have two scholars each (or three or four may be used if desired.)

"The five spelling blocks each have two vowels, so that each letter of the alphabet 85 occurs once and the vowels, A, E, I and O, twice. A sixth block, having an extra C, L, P, R, S and T, may be used when a greater variety of possible words is desired.

"*Start.*—Each player places all of his 90 scholars in the home on his right and then draws a block at random. The player drawing the block bearing the letter 'Z' takes all the blocks and throws them in his field. 95

"*Play.*—If he is able to spell any word or words with any of the letters on the top faces of the blocks (not using any of the letters twice), he calls it out and moves one of his scholars one space for each letter 100 used. For instance, 'Truce' gives five spaces. 'Boy' and 'In' give five spaces. 'Ten,' 'A' and 'I' give five spaces. A second throw is allowed when five points are made on first throw. When a player moves his scholar or 'gives up,' the next player on the left must take the blocks at once and throw them in his field. 105

"*Moves.*—Scholars may be moved straight or diagonally ahead from square 110 to square in the yard. One scholar may not jump over another, but may pass around if

an adjacent space is vacant. A scholar may re-enter his home only on making the exact number of points required to reach it. The player first bringing all of his scholars around the yard to the right and home—wins.

“Safety.—Scholars in the corners of the yard or on the steps on each side of the school house are ‘safe,’ otherwise, when overtaken by an opponent they may be sent back to the vacant safe spot last passed. If no safety is vacant, the scholar caught must return home and start over again.

“Time.—If a player is slow in finding a word and does not ‘give up,’ any opponent may begin to count out loud, slowly, 5—10—15, etc. If the player does not find a word before ‘100’ is called, his turn is ended. If the opponent has seen a word, he may call it out as soon as he reaches ‘100,’ and move his own scholar accordingly. If an opponent finds a word or words using more letters than those claimed or letters not used by a player, he counts out 5—10—15, etc., and is entitled to the extra points not used by the player, unless the player finds a word or words of equal length before 100 is called.

“Errors.—An error in spelling, calling or calling attention to a supposed error, by mistake puts a scholar back five spaces. The person discovering an error is entitled to five points. Errors should not count unless agreed beforehand.

35 “Blockades sometimes occur. Considerable skill is required to bring the scholars safely around the yard. An opponent’s scholar on a safety space in a corner of the yard will prevent a scholar from leaving or 40 entering the home thus guarded. It is best to get the scholars out early in the game and keep possession of safety spaces as much as possible, particularly taking care to guard your own home. When all of a 45 player’s scholars are blocked he loses his turn.

“Partners may be played by four people, two against two. The play and moves are the same as before, but one partner can help the other to find words. ‘Two 50 heads are better than one.’ This is a particularly good game for two children and two older people.”

What I claim is:

1. Game apparatus comprising a board 55 having fields and spaced paths, a set of five or more lettered pieces for throwing on the fields, each having two vowels and four consonants, the pair of vowels on each piece being different from the pair of 60 vowels on each of the other pieces and counters for moving on the paths in accordance with the words spelled.

2. Game apparatus comprising a board 65 having spaced paths, a set of six lettered pieces for throwing on the board, five of said pieces having two vowels each and four consonants, and the other piece having duplicate consonants, and counters for moving on the paths in accordance with the 70 words spelled.

3. Game apparatus comprising, a board 75 having home spaces, fields and spaced paths, a set of cubical pieces having different letters on the different sides for throwing on the fields, the principal vowels and consonants occurring more than once, and men for moving on the paths in accordance with the words spelled.

4. Game apparatus comprising a board 80 having spaced paths, men for moving on the paths and five lettered pieces bearing respectively the letters A—I—F—G—L—R, E—O—H—J—P—V, I—Y—C—M—X—Z, A—O—B—Q—S—T, E—U—D—85 K—N—W.

Signed at New London Conn. this third day of August 1906.

RICHARD W. MANSFIELD.
